[57] CLAIM

The ornamental design for a three phase distribution cluster mount, as shown and described.

DESCRIPTION

FIG. 1 is a right side elevational view of a three phase distribution cluster mount showing my new design, the broken line showing of the utility pole and electrical conductors being for illustrative purposes only and forming no part of the claimed design;

FIG. 2 is a left side elevational view thereof;

FIG. 3 is a top plan view thereof;

FIG. 4 is a bottom plan view thereof;

FIG. 5 is a front end elevational view thereof;

FIG. 6 is a rear end elevational view thereof;
FIG. 7 is a right side elevational view of a three phase distribution cluster mount showing a second embodiment of my new design, the broken line showing of the utility pole being for illustrative purposes only and forming no part of the claimed design;

FIG. 8 is a left side elevational view thereof;

FIG. 9 is a top plan view thereof;

FIG. 10 is a bottom plan view thereof;

FIG. 11 is a front end elevational view thereof; and

FIG. 12 is a rear end elevational view thereof.
